UNITED STATES PATENT OFFICE.

JÁNOS MÉSZÁROS, OF EAST MILLSBORO, PENNSYLVANIA.

RAIL-JOINT.

1,331,447.

Specification of Letters Patent. Patented Feb. 17, 1920.

Application filed September 26, 1919. Serial No. 326,425.

To all whom it may concern:

Be it known that I, JÁNOS MÉSZÁROS, a citizen of Hungary, residing at East Millsboro, in the county of Fayette and State of Pennsylvania, have invented new and useful Improvements in Rail-Joints, of which the following is a specification.

This invention has reference to improvements in means for connecting the meeting 10 ends of railway rails.

In carrying out my invention it is my purpose to produce rails having means integrally formed at the ends thereof for co-engaging with similar rails whereby a perfect 15 joint is produced between the rails without absolutely necessitating the employment of fish plates or other connecting means.

It is a further object of the invention to produce an improved means for connecting 20 the meeting ends of rails wherein each of the rails is provided at one of its ends with a base extension having a wedge slot or opening therein and the other end having a wedge tongue to be received in the slot of 25 the coacting rail whereby the rails may be easily, quickly and effectively connected.

The foregoing objects and others which will appear as the nature of the invention is better understood may be accomplished by 30 a construction such as is illustrated by the accompanying drawings.

In the drawings:

Figure 1 is an elevation of a plurality of rails constructed in accordance with this invention.

Fig. 2 is a greatly enlarged transverse sectional view approximately on the line 2—2 of Fig. 1.

Fig. 3 is a horizontal sectional view approximately on the line 3—3 of Fig. 1.

Fig. 4 is a plan view of one of the rail ends.

Fig. 5 is a bottom plan view of the other end of the rail.

Fig. 6 is a perspective view of the rail end illustrated in Fig. 4.

Fig. 7 is a similar view of the rail end illustrated in Fig. 5.

All of the rails are similarly formed and 50 therefore the reference characters denoting the parts of one may be understood as equally applicable to similar parts illustrated in the other rails.

Each of the rails is broadly indicated by

the numeral 8 and has its body portion constructed in the usual manner to include a head 9, a base 10 and a web 11 connecting the head and base.

The base 10 may, if desired, be of a greater thickness than that of the ordinary rail, but in any event the base at one of the ends of the rail is provided with an extension 12 which is of a thickness greater than that of the ordinary rail or greater than the base proper of the rail illustrated. This 65 extension presents a flat top, and, of course, a flat bottom. The extension from the outer end thereof is formed with a dove-tailed slot or notch 13. The angle side walls of the notch 13 are preferably inclined or beveled inwardly from the top to the bottom of the extension 12.

The base portion at the opposite end of the rail 8 is formed with a dove-tailed tongue 14, the said tongue having its outer end terminating with the outer end of the rail proper and extending inwardly of the rail a length equaling that of the length of the notch 13. The side walls of the tongue 14 are beveled in an opposite direction to the beveled side 75 walls of the notch 13, so that a snug engagement between the said side walls of the tongue and the said side walls of the notch will be effected when the rails are connected. In addition to this, the beveled walls of the 80 tongue limit the downward movement of one of the rails, as the co-engagement therewith with the inwardly inclined beveled walls of the notch prevent the first mentioned rail end being moved downwardly through the 90 notch a distance sufficient to bring the heads of the co-engaging rails out of disalignment.

In connecting the rails, one of the rails provided with the tongue has its end elevated over the flat extension 12 of a rail which is secured to the ties so that its tongue may be readily slid into the notch of the second mentioned rail. Thereafter the last mentioned rail is spiked to the ties 15, and 95 in this manner the track may be easily and quickly laid. While with my construction the employment of fish plates is not an absolute requirement, such plates may be employed if desired.

Having thus described the invention, what is claimed as new, is:—

Railway rails each having one of its ends

provided with a thickened extension presenting an upper flat surface which is formed with a dove-tailed slot that enters from the outer end thereof and the side walls provided by the slot being beveled inwardly, the other end of the rail having a thickened dove-tailed tongue at the end

thereof which extends inwardly and which has its side walls beveled in an opposite direction from those of the notch, and the tongue of one of the rails designed to be received in the notch of the co-acting rail.

In testimony whereof I affix my signature.

JÁNOS MÉSZÁROS.
